UNITED STATES PATENT OFFICE.

EDWARD L. GARFIELD, OF CRESTWOOD, NEW YORK.

WASHING MACHINE.

Application filed December 30, 1924. Serial No. 758,799.

This invention relates to machines useful in washing or otherwise subjecting materials to fluid action, and has more particular reference to a type capable of being employed in the additional capacity of moisture eliminators or extractors.

Amongst the objects of my invention are to render conversion of a machine of the character specified from one used to the other without entailing complicated adjustments, and without necessitating removal of the treating fluid; to make possible the employment of the fluid itself as the medium to operate the machine, and at the same time effect efficient circulation thereof through and about the materials, to the end of rendering the treatment correspondingly more thorough and effective.

Other objects and attendant advantages according to my invention will be readily apparent from the detailed description herein-after of the typical embodiment thereof shown in the drawings, whereof Fig. I is an axial sectional view showing the machine in the upright position in which it is used as a moisture extractor subsequent to washing.

Fig. II is a side elevation of the same.

Fig. III is a cross section, in plan, taken as indicated by the arrows III—III in Figs. I and II.

Fig. IV is a view similar to Fig. I but showing the machine in the position to which it is tilted when used for washing; and,

Fig. V is an enlarged detail view, in section, showing the means employed to rotate the basket or drum containing the materials being treated.

In these illustrations, 1 indicates a container for washing fluid which is preferably cylindric and supported by an attached sub-frame 2, the latter having one portion straight or parallel to the bottom of said container as at 3; and the other portion obtusely inclined as at 4 so as to afford different bases whereby the machine may be sustained in stable equilibrium, either in the upright position shown in Fig. I, or the tilted position of Fig. IV.

As a means to assist in stabilizing the machine in the upright position, supplementary legs, such as shown at 5, may be provided, pivotal connection with the container 1 as at 6, permitting said legs to be swung upward out of the way when the machine is to be tilted to the position of Fig. IV.

Concentrically disposed within the con-

tainer 1 is an open-topped drum-shaped basket 7 of perforate material which is supported at an elevation above the container bottom by a vertical bearing 8, wherein is freely journaled its depending axis or shaft 9. Rigidity of the bearing 8 against sidewise displacement is insured by a number of angular buttress struts 10. About the lower portion of its exterior, the basket 7 is equipped with a circumferential series of turbine blades 11 that lie in the path of a nozzle 12, at the upper end of a pipe 13 extending downward through the bottom of the container 1 to a centrifugal pump 14, which is appropriately supported by the sub-structure 2. Under propulsion of a directly connected electric motor 15—or its equivalent—the pump 14 draws washing fluid, through an elbow 16, from the container 1, such pumped fluid being discharged from the nozzle 12 against the turbine blades 11 in the manner shown in Fig. V, and thus continuously rotating the basket 7.

In operation, the container 1 is filled with washing fluid F to a level slightly below the bottom of the basket 7, whereupon the materials to be washed are placed in the latter. The machine is then bodily tilted onto the sub-frame obtuse-angled portion 4, or as shown in Fig. IV, and the motor 15 started. As a consequence of tilting, the basket 7 will run at reduced speed due to partial immersion in the washing fluid F, whereupon the material will be slowly tumbled about and at the same time treated to the constantly changing seepage through the basket perforations. Also concurrently with the discharge of the nozzle 12 against the turbine blades 11, part of the fluid stream finds its way through the perforations of the basket 7 (see Fig. V) and is forcibly impinged upon the materials, thereby greatly adding to the thoroughness of the treatment. After the lapse of the proper time period necessary to complete washing, the machine—still running—is turned to the upright position of Fig. I, the basket 7 being thus raised clear of the fluid F. As a consequence of the removal of the drag of immersion, the basket 7 will now rotate at a greatly increased speed such as will preclude the possibility of the fluid F from the nozzle 12 entering the basket perforations. In this phase of the operation, the machine will therefore function as a centrifugal moisture eliminator, rendering the employment of a wringer unnecessary, the extracted excess fluid F draining back into the

container 1, through the apertures in the bottom of the basket 7. The washing fluid F may, accordingly, be re-used as often as desired without appreciable waste.

5 Although herein described as particularly adapted for washing, the machine of my invention may obviously be employed with equal advantages in such use, for bleaching, dyeing and kindred operations. The term 10 "washing" appearing in the claims is therefore, to be construed as sufficiently comprehensive to include the several treatments mentioned.

Having thus described my invention, I 15 claim:

1. In a washing machine, the combination of a container for washing fluid; a basket for the materials being washed rotatable within the container; and a supporting structure therefor embodying two faces, one of which is parallel to the bottom of the container and connected thereto, while the other is arranged obtusely to the first mentioned face and connected therewith as well as to 20 said container, said base serving to sustain the machine without adjustment of any part or parts in stable equilibrium either vertical or in an inclined position, whereby the basket may be rotated entirely clear of the fluid or 25 partially immersed therein, respectively.

2. The combination, in a washing machine, of a container for washing fluid; a supporting base therefor having two faces, one of which is parallel to the bottom of the container and connected thereto, while the other is disposed obtusely to the first mentioned face and connected thereto as well as to the container, so as to support the machine without any adjustments in stable equilibrium 30 with said container vertical or in an inclined position; a perforated basket, having a circumferential series of turbine blades, for the material being washed rotatable on an axis within the container so as to run partially immersed in the fluid when the machine is tilted; and means for elevating fluid from the container for impingement upon the basket turbine blades to effect rotation thereof and saturation of the contained material, or to 35 eliminate moisture from said material.

3. The combination, in a washing machine, of a container for washing fluid; a sub-frame having two faces affording individual supporting bases, one of said faces being parallel 40 to the container bottom and serving to stabilize the machine when vertical, while the other of said faces is arranged obtusely to the first mentioned face for support of the machine in equilibrium when inclined; a perforated basket, having circumferential turbine blades, for the materials being washed, said basket being rotatable about an axis and supported in spaced relation within the container so as to be partially immersed when the machine is tilted; and means for elevating fluid 45

from the container for impingement upon the turbine blades about the basket to effect rotation thereof.

4. The combination, in a washing machine, of a container for washing fluid; a base to support the machine, said base having two faces, one of which is parallel with the container bottom and connected thereto, while the other is arranged obtusely to the first mentioned face and connected thereto as well as to the container, so as to sustain the machine in stable equilibrium with the container vertical or in an inclined position; supplemental means to assist in stabilizing the machine when vertical; a perforated basket for the materials being washed having a circumferential series of turbine blades, said basket being rotatable on an axis and supported in spaced relation within the container so as to be partially immersed in the washing fluid when the machine is tilted; and means for elevating said fluid from the container for impingement upon the turbine blades about the basket to effect rotation of the latter.

5. The combination, in a washing machine, of a container for washing fluid; an attached sub-frame with two supporting faces, one of which is parallel to the bottom of the container, while the other is arranged obtusely to the first mentioned face and in continuity therewith, said faces respectively serving to stabilize the machine in either a vertical or an inclined position; supplemental members pivoted below the container to assist in stabilizing the machine when vertical; an open-top perforate basket for the materials being washed having a series of external turbine blades, said basket being supported at an elevation above the container bottom by a depending axis and rotatable when the machine is either vertical or tilted; and means for elevating fluid from the container for impingement upon the turbine blades about the perforated basket to effect rotation thereof and saturation of the contained material, or to 100 eliminate moisture therefrom.

6. In a washing machine, the combination of a container for washing fluid, said container having an attached sub-frame embodying relatively obtuse-angled supporting faces; a basket for the materials being washed with a circumferential series of external turbine blades, said basket being rotatable within the container; and means for imparting motion to the fluid and for utilizing the energy due to such motion to rotate the basket by impingement on the turbine blades aforesaid.

7. In a washing machine, the combination of a fluid container; an attached base with two supporting faces, one of which is parallel to the container bottom while the other is disposed obtusely to the first mentioned face, said base being adapted to sustain the machine in a vertical or an inclined position; a

5 basket for the materials being washed rotatable within the fluid container and having a circumferential series of turbine blades about its lower exterior surface; and means for imparting motion to the fluid and utilizing the energy resulting therefrom to rotate the basket by impingement on the turbine blades, said means including a pump continuously drawing fluid from the container and a nozzle 10 functional to direct the discharging fluid against the aforesaid turbine blades, about the rotatable basket.

8. In a washing machine, the combination of a fluid container; an attached base having 15 co-extensive faces, one of which is parallel with the container bottom while the other is disposed obtusely relative to the first mentioned face, said base being adapted to support the machine in a vertical or in an inclined position; a basket for the materials being washed rotatable within the fluid container and having a circumferential series of turbine blades about its lower exterior surface; and a pump with flow connections for 20 imparting motion to the fluid to rotate the basket by impingement on the turbine blades aforesaid, and, at the same time, to either effect saturation of—or moisture elimination from—the materials therein.

30 9. In a washing machine, the combination of a fluid container; an attached base having co-extensive faces, one of which is parallel to the container bottom, while the other is arranged obtusely to the first mentioned face, 35 said base being adapted to support the machine in a vertical or an inclined position; a basket for the materials being washed rotatable within the fluid container and having circumferential turbine blades about its lower 40 exterior surface; and a pump with a connection for drawing washing fluid from the container for discharge by way of a connected nozzle against the turbine blades to rotate the basket and, through the apertures of the latter, to effect saturation of the materials 45 therein.

10. A machine of the class described having in combination a container provided with a surface engaging portion, a drum revolvably mounted in the container, means for actuating said drum, and means connected to the container to support the machine in one position, said means coacting with said engaging portion to maintain the machine in another position. 50

11. A machine of the class described having in combination a container provided with a surface engaging portion, a drum revolvably mounted in the container, means for actuating said drum, and means connected to one end and the sides of the container to support the machine in one position and coacting with the surface engaging portion to maintain the machine in another position. 55

12. A machine of the class described having in combination a tiltable container provided with a ground engaging portion, a drum revolvably mounted in the container, a motor operatively connected to said drum, means for maintaining said drum in a predetermined relation to said container irrespective of the position of said container, and means attached to said container to support the machine in one position, said means coacting with the ground engaging portion for maintaining the machine in another position. 60

13. A machine of the class described having in combination a container provided with a ground engaging portion, a drum revolvably mounted in the container, means for actuating said drum, and supporting means connected to said container and having a supporting portion arranged at an angle to the axis of the drum to maintain the machine in one position and adapted to coact with the ground engaging portion for supporting the machine in a different position. 70

In testimony whereof, I have hereunto signed my name at New York, New York, this sixteenth day of December, 1924.

EDWARD L. GARFIELD.
